UNITED STATES PATENT OFFICE.

JAMES R. FARNHAM AND FRED F. SCHENK, OF PRINCETON, MINNESOTA.

BLOTTER ATTACHMENT FOR CHECK OR RECEIPT BOOKS.

SPECIFICATION forming part of Letters Patent No. 651,348, dated June 12, 1900.

Application filed January 31, 1900. Serial No. 3,469. (No model.)

To all whom it may concern:

Be it known that we, JAMES R. FARNHAM and FRED F. SCHENK, citizens of the United States, residing at Princeton, in the county 5 of Mille Lacs and State of Minnesota, have invented a new and useful Blotter Attachment for Check or Receipt Books; of which the following is a specification.

This invention relates to a blotter attachment for check or receipt books or analogous devices; and the object of the same is to apply a simple and effective blotting device to a book of the character set forth in such manner that a portion thereof may be employed 10 to blot a stub and turned back to clear the stub for filling in the latter and inseparably held in movable relation to the main body of the blotter of such dimensions as to cover almost the entire face of a check or stub and 15 movable toward and from the latter from a point other than the jointure or binding of the backs or covers and leaves.

The invention consists in the construction and arrangement of the several parts, which 20 will be more fully hereinafter described and claimed.

In the drawings, Figure 1 is a perspective view of a check or receipt book shown open and having the improved blotting attachment 25 applied thereto and the movable stub portion thereof elevated to expose the stub. Fig. 2 is a longitudinal vertical section of a check or receipt book and the improved attachment. Fig. 3 is a detail perspective view of the blotter attachment looking toward the side opposite that shown by Fig. 1.

Similar numerals of reference are employed to indicate corresponding parts in the several views.

The numeral 1 designates a receipt, check, or other analogous book having separable leaves to leave a record-stub intact with the book, and in the present instance the said stubs have the designating matter printed or 40 otherwise applied thereto in a transverse direction, as at 2, and clearly shown by Fig. 1. As usual in books of this character the leaves and stubs are inclosed by or bound between movable covers 3, and the essential feature 45 of the improved device is the application of a blotter attachment to the book at a point other than the usual place of attachment and

which is to the front cover or at the hinge thereof. This particular arrangement is for the purpose of entirely clearing the leaves of 55 the book, if desired, or to permit a blotting operation to be carried on without requiring the closure of the cover carrying the blotter, as in the old construction, and also to allow a clearance of the stub without exposing the 60 leaf connected thereto, and thereby prevent spoiling the leaf by accidental blotting or dis-coloring it by resting the hand thereon while filling in the stub.

The improved attachment comprises a blotter 4, which has a break-line 5 to provide a movable stub-section 6, and extending full length of the upper side of the said blotter is a reinforce connecting-strip 7, preferably of textile fabric, which strengthens the blotter 70 and also prevents the section 6 from being disconnected by constant use. This reinforce-strip 7 is adhesively or otherwise secured to the blotter and made longer than the latter, so as to extend around the free ends of the 75 leaves, as clearly shown in Fig. 2, and be secured to the outer surface of the back-cover 3 at the rear. The portion of the reinforce which extends over the free ends of the checks or receipts is not attached to said ends, and 80 this particular loose portion of said reinforce is long enough to cover or extend over all the ends of the checks or receipts. By thus securing the textile-fabric reinforce to the back-cover 3 as stated the blotter is always held 85 in connection with the book and free to be thrown outwardly from engagement with the leaves to permit separation thereof from the stubs or to be thrown inwardly for blotting operations, as clearly illustrated by Fig. 1. 90 The movable section 6 permits the stub to be exposed for receiving the record matter pertaining to the check or receipt attached thereto, while the main portion of the blotter remains on the said check or receipt, and after 95 filling the stub the section 6 may be conveniently turned thereover to blot the wet ink and the blotter attachment entire afterward thrown outwardly to clear the check or receipt, which is filled in in accordance with the 100 data on the stub attached thereto. The blotter attachment is then returned to the position shown in Fig. 1 to blot the set ink of the check or receipt and again thrown outwardly

to separate the said check or receipt from its stub.

The blotter 4, with the reinforce, may be applied to any form of blank book and serve 5 efficiently as a ready and convenient means for drying ink.

The improved device is capable of a wide range of modification within the purview of the invention, and though the preferred form 10 of the device has been shown it is obvious that changes in the form, proportions, and minor details may be resorted to without departing from the principle or sacrificing any of the advantages of the invention.

15 Having thus described the invention, what is claimed as new is—

1. The combination with a check or receipt book comprising stubs and separable checks or receipts, of a blotter attachment having a 20 break-line adjacent one extremity and registering with the line which divides the checks from the stubs whereby the blotter is adapted to fold back on the main body of the blotter to clear the stubs or to be brought over the 25 latter for blotting purposes, and a reinforce fabric secured to one face of the blotter and extending the full length thereof, said reinforce fabric being projected beyond a portion of the blotter and over the edges of the checks 30 or receipts attached to a part of the back-cover, the portion of the fabric reinforce between its attached extremity on the back-

cover and the adjacent extremity of the blotter being loose for extension over the edges of the receipts or checks.

2. The combination with a check or receipt book having a plurality of checks or receipts separably connected to stubs, of a blotter attachment having a break-line extending transversely thereof adjacent one terminal, 40 and registering with the line which divides the checks from the stubs whereby the blotter is adapted to form a movable section to blot the stubs or clear the same while the body portion of the blotter covers the receipts or checks, 45 and a reinforce secured to and extending over the full length of the outer face of the blotter-body to provide a hinged connection for the said movable section and to prevent tearing of the said body part of the blotter, the reinforce being extended over one end of the blotter and secured to the outer face of the back-cover, the loose portion of the reinforce between the end of the blotter and the edge of the back-cover being adapted to extend over 55 the edges of the checks or receipts.

In testimony that we claim the foregoing as our own we have hereto affixed our signatures in the presence of two witnesses.

JAMES R. FARNHAM.
FRED F. SCHENK.
